UNITED STATES PATENT OFFICE.

CHARLES EVAN FOWLER, OF NEW YORK, N. Y.

CAISSON AND METHOD OF MAKING THE SAME.

Application filed December 5, 1923. Serial No. 678,742.

To all whom it may concern:

Be it known that I, CHARLES E. FOWLER, a citizen of the United States, and a resident of the city of New York, borough of 5 Manhattan, in the county and State of New York, have invented a new and Improved Caisson and Method of Making the Same, of which the following is a full, clear, and exact description.

10 This invention relates to improvements in caissons and the method of making the same, an object of the invention being to provide an improved construction of caisson for foundations of buildings or other structures which affords effectual resistance to downward movement by reason of an improved construction and arrangement of fins or fans integrally formed thereon.

15 The use of wells or caissons for foundations of buildings, or other structures such as ordinarily made, does not afford sufficient bearing area on the bottom for anything except rock, where large loads are to be carried and it is, therefore, necessary to 20 rely upon skin friction which is uncertain and of doubtful value and it is the purpose of my invention to provide a construction having an improved arrangement of fins or fans integrally formed on the caisson and 25 properly arranged and proportioned so as to give efficient results under all conditions.

30 A further object is to provide improved steps of a method whereby the earth can be properly formed as a mold into which 35 the concrete re-enforced as may be desired, may be located and shaped to form my improved caisson.

35 The invention, therefore, consists in certain features of construction and combinations and arrangements of parts and in certain novel steps in the method, all of which will be more fully hereinafter described and 40 pointed out in the claims.

45 In the accompanying drawings—

Figure 1 is a view in side elevation of my improved casing or form which is built up and positioned in the well in carrying out my improved method.

50 Figure 2 is an end view of Figure 1.

Figure 3 is a view in longitudinal section, showing the earth with the well properly

formed therein so that when filled with concrete, will result in a caisson of my improved construction.

Figure 4 is a view partly in elevation but mainly in longitudinal section, showing the completed caisson in the ground.

Figure 5 is an end view of a slightly modified form of caisson.

Figure 6 is a view in side elevation of the caisson shown in Figure 5.

Figures 7 and 8 are views similar to Figures 5 and 6, illustrating another modification.

In carrying out my improved method, 65 I employ a form or casing 1 indicated in Figures 1 and 2 which is built up or otherwise positioned within a well 2 which is formed in the ground 3. This casing 1 is composed of a plurality of circular series 70 of relatively short and narrow staves 4 which are held in proper relation to each other and to the well by means of expandable rings 6 which may be rendered adjustable in any approved manner.

75 After the well 2 is formed in the ground and the casing 1 positioned therein, certain of the staves 4 can be removed by loosening the rings 6 and through the openings in the casing 1 provided by the removal of these 80 staves, the workmen can cut recesses 5 in the earth at the wall of the well so that when the casing is removed and the well filled with concrete, these recesses 5 will constitute molds and the concrete shaped therein to form fins 7 on the caisson 10 such as shown in Figures 4, 5 and 6 or fans 8 such as shown in Figures 7 and 8. It is of course 85 to be understood that after the fin holes are made the form in its entirety is removed and the concrete poured into the mold to form a pile or caisson.

90 In the construction illustrated in Figures 3 and 4, but single staves or portions thereof are removed and the fins 7, which are thus provided after the caisson is made, are 95 relatively narrow and are arranged in circular series with the fins of adjacent series having staggered relation to each other. Furthermore, I would call attention to the fact that the lowermost fins project laterally 100 from the body of the caisson a relatively

short distance while the fins of the succeeding series upwardly project increasingly in relative proportion. Hence, the shortest fins are at the lower portion of the caisson 5 and the longest fins adjacent the top. By reason of this construction, an equalizing of resistance to downward movement is had because it is a well known fact that the resistance of the earth at the surface is appreciable less than at the lower points and proportionately so. Hence, by projecting the lugs or fins proportionately and in regular ratio an equilibrium of the resistance is provided. To strengthen the fins or lugs, 10 I preferably locate re-enforcing bars 9 therein, said bars being of varying sizes according to the length of the fin and embedded both in the fin and in the body of the caisson. I would also call attention to 15 the fact that the lower faces of all the fins or lugs are flat and at a right angle to the surface of the caisson, the other outer surfaces of the fins being of any desired shape but preferably giving to the fin a general taper 20 inwardly from its lower to its upper end. 25 In constructing a caisson such as illustrated in Figures 5 and 6 where the fins are appreciably wider than that shown in Figure 4, more than one of the staves of the casing 1 can be removed and the shape of the fins or lugs controlled entirely by the desire of the builder. 30 In constructing a caisson such as shown in Figures 7 and 8 where annular fans are 35 formed on the caisson, it is, of course, necessary to remove an annular series of staves in order to permit the proper recessing of the well wall to provide a mold for said fans. 40 It is obvious that a great latitude is possible in the shape and arrangement of fins, lugs or fans which may be formed on the caisson without departing from the invention and, hence, I do not wish to be limited 45 to the precise shapes or designs shown as

these may be varied within the spirit and scope of the appended claims.

What I claim is:—

1. A caisson, comprising a body, and radially projecting fins of varying lengths 50 integral with the body.

2. A caisson, comprising a body, projections on the body at different elevations, 55 said projections increasing in length in regular ratio upwardly.

3. A caisson, comprising a body, a plurality of circular series of outwardly projecting lugs or fins of varying lengths on the body, the fins of adjacent series having 60 staggered relation to each other.

4. A caisson, comprising a body, a plurality of circular series of outwardly projecting lugs or fins on the body, the fins of adjacent series having staggered relation to each other, and the fins of the respective 65 series increasing in length in regular proportion upwardly.

5. The herein described method, consisting in forming a well, locating a casing in the well, removing sections of the casing, 70 cutting molds in the wall of the well by inserting an instrument through the casing then removing the casing, and then filling said well and recesses with a composition to form a caisson.

6. The herein described method of forming caissons, consisting in first providing a well in the ground, then positioning a sectional casing or form in the well, next removing sections of the casing, then inserting an instrument through the openings in the casings thus formed and shaping recesses in the wall of the well, then removing the casing and next pouring concrete into the well to fill the same and the recesses and during such pouring locating re-inforcing bars in the fins formed in the recesses and 85 in the body of the caisson.

CHARLES EVAN FOWLER.
